EASEL

Alfred James Moir, Toronto, Ontario, Canada

Application November 29, 1951, Serial No. 258,801

6 Claims. (Cl. 45—129)

1

This invention relates to improvements in easels for supporting the artist's work when painting and sketching.

The principal object of the invention is to provide an easel which will securely hold the artist's work in any position of inclination either towards or away from him.

A further and important object is to enable adjustment of the angle of the work to be quickly and easily accomplished.

Still a further object of importance is to provide an easel as aforesaid of simple and attractive construction which can be conveniently collapsed to an extremely compact unit for carriage and can be extended to hold substantially any size of painting normally encountered, and in extended position can be mounted on a small table or other support eliminating the present cumbersome supporting bases.

Still a further object is to enable the artist to carry his paints, oils and brushes in his easel for convenience.

The principal feature of the invention resides in pivotally supporting from a base an adjustable cantilever extension in the form of a plurality of pivotally connected arms or segments and carrying at the free end means to engage the upper edge of the work being held with the arms adjusted to incline the work at the desired angle, the arms carrying means to lock them in adjusted position into a rigid structure pivotal about the base and providing means to swing the rigid structure thus formed about its pivotal connection to the base to apply downward pressure on the work clamping it firmly against the base.

A further feature resides in operating the cantilever structure to swing about its base pivot by means of a screw operator to thereby afford continuous adjustment.

Another feature resides in forming the pivotal arm arrangement of the cantilever to collapse into a compact formation lying within the dimensions of the base.

Another feature resides in forming the base as a container adapted to house the artist's supplies with the base portion from which the cantilever is pivotally supported forming a hinged closure for the container.

These and other objects and features will become apparent from the following description taken in conjunction with the accompanying drawings in which

Figure 1 is a plan view of an easel constructed in accordance with the invention.

Figure 2 is a side elevational view of the easel of Figure 1.

Figure 3 is a rear elevational view showing the cantilever adjustment mechanism.

Figure 4 is a side elevational view showing the adjustment feature of the cantilever arms.

2

Figure 5 is a view showing the easel collapsed and showing in dotted line the easel "opened" to give the artist access to the base.

Referring to the drawings, the easel comprises a base 1, preferably in the form of a tray to house the artist's supplies and closed by a top board or cover 2 hinged to the base at 3 and limited in its opening movement by links 4 and locked in its closed position by a latch 5.

10 Carried on a U bracket 6 mounted at the rear of the cover 2 are a pair of arms 7 pivoted to the bracket 6 on bolts 8 operated by wing nuts 9 to draw the arms into clamping engagement with the bracket surfaces 10. Suitable resilient or rubber washers 11 are incorporated between the surfaces 10 and the arms 7 to provide a firm friction grip therebetween upon tightening the wing nuts 9.

Extending transversely between the arms 7 is 20 a bar 12 adapted to rotate about an axis transverse the arms, and extending through this bar is a threaded adjusting member 13 in the form of a length of rod having its lower end right angularly bent and pivoted at 14 to swing about a 25 pivotal axis parallel the pivotal axis of the arms 7.

The arms 7 form the first segment of the cantilever structure of the easel while the second segment is formed by wide arm 15 pivoted between the upper ends of the arms 7 on a bolt 16 operated by wing nut 17 to draw the arms into clamping engagement. Suitable friction washers 18 corresponding to the members 11 are interposed between the arm 15 and arms 7 to provide on compression a firm frictional grip between the arms.

35 The next segment of the cantilever structure is formed by a pair of arms 19 pivoted on opposite sides of the arm 15 by means of the bolt 20 operated to clamp the arms by a nut 21 in the same manner as the previous arms.

40 Further arms 22 are pivotally connected to the ends of arms 19 again with suitable clamping bolts and nuts 21—22 respectively, and these arms carry a transverse support surface 23 through which project clamps 24 operated by the wing nuts 25.

In supporting his work 26, which may be a board on which his canvas is mounted or a frame carrying means for supporting his working surface, the artist seats the lower edge of the work in the V 27 of the brackets 28 carried by the base. He then adjusts the angular relation of the arms 7, 15, 19 etc. (see Figure 4), so that the upper edge of the work is received beneath the clamps 24 with the work at approximately the desired inclination.

During this adjustment period the bolts 8, 16 etc. may be tightened sufficiently to maintain the arms in any angular relation to which they are set under their own weight, although 60 permitting forceful displacement. With the up-

per edge of the work clamped the bolts 8, 16 etc. are tightened to convert the cantilever structure or extension formed by the arms into a rigid structure. This rigid structure is then bodily rotated on the bolts 8 by means of a wing nut 29 operating on the adjusting member 13 against the bar 12.

Since the cantilever structure when clamped is rigid, the movement imparted to its free end gripping the work will move towards the base 1 as the cantilever is rotated providing an increasing pressure down on the work against the base. There will be a small shift in the inclination of the work during this clamping motion but this can be allowed for in the original setting of the arms. Any degree of pressure desired can be obtained by operation of the wing nut 29 until the work is held absolutely rigid in its desired position.

A lock nut 30 on the member 13 serves to secure the adjustment and additionally, wing nuts 9 can be operated to further increase the lock of the cantilever in its work-clamping relation.

Figure 4 shows in solid line the work inclined away from the artist, which is usual when painting water colours, while in dotted line it shows the work inclined towards the artist, usual when painting oils. The actual angle of inclination can be increased to any desired angle.

It will be appreciated that, regardless of the angle of the work desired, the cantilever structure can be actuated to securely clamp the work firmly against movement, providing a highly desirable working surface.

The base is formed of sturdy construction and it will be appreciated that the easel may be used on a small table taking up the minimum of space, or where the easel is used on a larger table sufficient table surface will be afforded on which the artist can place his necessary working utensils.

Figure 2 shows the arrangement of the cantilever where a smaller piece of work 31 is being held and again it will be seen that the adjustment of the arms readily permits accommodation of this work.

Figure 5 shows the manner in which the arms of the cantilever can be collapsed to internest with the face of the support surface 23 down against the base portion 2, being held from marking this portion by rubber studs 32.

Figure 5 shows in dotted line the position of the cantilever when the cover 2 is swung upwardly, giving access to the base 1, allowing a considerable storage space.

Handles 33 form a convenient means for carrying the easel when collapsed to the configuration of Figure 5 and the cover 2 locked in closed position by the latch 5.

It will be understood that variations in the form of the cantilever arms and other structural details may be made without departing from the scope of the invention.

What I claim as my invention is:

1. An easel comprising a base, an adjustable cantilever extension pivotally supported from said base, said extension comprising a plurality of arms pivotally connected in end-to-end relation, means at the free end of said extension to support the upper edge of a piece of work mounted on said base, means locking said pivotally connected arms in pivotal adjustment with the

work inclined approximately at a desired angle to form a rigid cantilever structure pivotal about said base, and means pivoting said rigid cantilever structure relative said base to apply downward pressure on the work clamping it against said base.

2. A device as claimed in claim 1 in which said means for pivoting said rigid cantilever structure comprises a screw-threaded member providing continuous adjustment of the cantilever movement, and means to lock the rigid cantilever structure in adjusted position.

3. A device as claimed in claim 1 in which the base is provided with a V formation to receive the lower edge of the work.

4. An easel comprising a base and an adjustable cantilever extension pivotally supported from said base, said base being adapted to support the lower edge of a piece of work placed thereon, said extension comprising a plurality of pivotally connected sections and having means at the free end thereof to engage the work adjacent the upper edge thereof, means locking said pivotally connected sections in pivotal adjustment to form a rigid cantilever structure, and means locking said rigid cantilever structure thus formed from pivotal movement about said base.

5. An easel comprising a base and an adjustable cantilever extension pivotally supported from said base, said extension comprising a plurality of pivotally connected extension sections, means carried at the free end of said extension to engage work to be supported on said base in an inclined position, means carried by said sections for locking same in pivotal adjustment when set to support the work in inclined position, converting said extension into a substantially rigid cantilever pivotal about said base, a longitudinal member pivoted to rotate on an axis parallel to and offset from the pivot axis of said rigid cantilever and extending longitudinally in the direction of said cantilever, and means carried by said member to engage said cantilever and rotate same about its pivotal connection with said base while following the pivotal movement of said cantilever.

6. An easel as claimed in claim 5 in which said cantilever has a transverse member having an opening therein and said longitudinal member comprises a rod pivoted to said base and having a screw-threaded end extending through said opening, a nut member on said threaded end engaging said cross member, and means locking said cantilever in position upon adjustment by operating said nut member against said cross member.
